UNITED STATES PATENT OFFICE.

EDWIN V. BABBITT, OF FAIRHAVEN, MASSACHUSETTS.

DESIGN FOR A DOLL.

Application filed January 12, 1926. Serial No. 16,029. Term of patent 14 years.

To all whom it may concern:

Be it known that I, EDWIN V. BABBITT, a citizen of the United States, residing at Fairhaven, in the county of Bristol and State of Massachusetts, have invented a new, original, and ornamental Design for a Doll, of which the following is a specification, reference being had to the accompanying drawing, forming a part thereof.

In the drawing,—

Fig. 1 is a front elevation; and
Fig. 2 is a side elevation of a doll embodying my new design.

I claim:

The ornamental design for a doll substantially as shown.

EDWIN V. BABBITT.
